UNITED STATES PATENT OFFICE.

BENJAMIN DOWICK, OF JERSEY CITY, NEW JERSEY.

SUSPENSION ADJUSTMENT DEVICE

Application filed April 22, 1926. Serial No. 103,793.

This invention relates to adjustment devices for suspension ropes, and particularly to devices for regulating the electric cords of ordinary drop lights, so as to adjust such lights to any desired elevation.

The principal object of my invention is to provide a simplified, inexpensive, efficient, compact, neat, and improved device for the above purpose.

10 Other objects and advantages will herein-after appear.

In the accompanying drawings,—

Fig. 1 is a general elevation of the device, with the casing shown as broken away.

15 Fig. 2 shows a rear elevation of the device.

Fig. 3 shows a sectional side elevation of the device.

Fig. 4 shows a detail of the device.

20 Fig. 5 is a general illustration, in a reduced scale, showing the device as it appears when operatively secured to the electric lamp cord.

The casing 1 of the device comprises a 25 back-plate 2, and a cover-plate 3. To the center of plate 2 is secured a stud 4 in the manner shown, upon which is rotatably mounted a sheave-pulley 5 having a peripheral groove 6 suitable for the reception 30 of the lamp cord 7. Said pulley is hollow and within it is located a coiled leaf-spring 8 having one end 9 thereof secured to the stud 4 and its other end 10 secured to the rim of the pulley 5, whereby said spring continually tends to rotate the pulley in a 35 clockwise direction, as viewed in Fig. 1. Upon the rear side of the wall 11 of the pulley are pivoted, at 12, two gravity-pawls 13 which coact with a pair of ratchet-grooves 14 formed in the stud 4 and with 40 a pair of abutments 15, which keep them from falling too far away, in the manner of the usual spring shade-roller action. The pulley 5 may be therefore freely rotated in 45 either direction when turned at a fair rate of speed, but is prevented from rotating counter-clockwise by either of said pawls, and contrary to the action of the spring 8, when the rotation is stopped. In the casing-plate 2 is formed a slot 16 through which 50 passes the locking end 17 of a grip-plate 18, and a screw 19 passes through a hole in plate 18 and threads into the casing-plate, by which means the casing can be se-

cured to the cord 7 in the manner shown in Fig. 4. The casing plate 2 carries a grooved pin 20, a curved ridge 21, and a grooved roller 22 for mounting and guiding the cord, as will be hereinafter seen. An arm 23 pivoted to the plate 2 at 24 carries a roll 25 having a grooved periphery 26, and a spring 27 wound around the pivot 24 continually bears upon said arm and causes pressure of the roll 25 against the cord 7, when the latter is wound around the pulley 5.

For mounting the device in operative state, the upper cord-portion 7^a is passed under the grooved pin 20, over the ridge 21, and between the plate 2 and grip-plate 18, where it is firmly secured with the screw 19. 60 A loop 28 is then formed of the cord 7, which is then passed around the pulley 5, and between the pulley and the roll 25, and then the cord is passed over the guide-roller 22 and outwardly from the casing, wherefrom it extends as the lower cord-portion 7^b that carries the lamp 29. By the aforesaid means of the disposition of the cord 7 within the casing 1, and by the provision of the pin 20, ridge 21, and roller 22, the device is maintained in symmetrical position relatively to the electric suspension cord, with the upper and lower cord-portions 7^a, 7^b and the center of the operating pulley 5 in perfect alignment, thereby imparting a 65 neat appearance to the installation. The roll 25 holds the cord 7 to the periphery of the pulley 5 while the latter propels the cord as well as while its rotation is stopped by the pawls 13. If desired, the grooved periphery of the pulley 5 may be lined with rubber 5^a, to aid the frictional hold of the cord against the pulley. When it is desired to place the lamp 29 at any elevation it is merely grasped and pulled or retracted, as 70 the case may be, in the manner of the ordinary spring shade-roller, and then left at the desired elevation. This pulling of the cord rotates the pulley 5 contrary to the force of the spring 8 and the retraction of the cord causes said spring to rotate the pulley backwardly, to take up the slack of the cord, and when the cord is released the pawls 13 act to arrest the pulley and retain the lamp in the adjusted position. As the 75 lamp is elevated the loop 28 is increased in size, and when the lamp is lowered the free loop is diminished in extent, the roll 25 at

all times holding the cord 7 to the pulley as the latter propels it. It will be evident that the device may be secured to the cord 7 at any place therealong. It will be also evident that while the device is here illustrated in connection with electric lamp cords, it may be similarly utilized in connection with other situations where an adjustment device may be required for suspension ropes or chains.

Variations may be resorted to within the scope of the invention, and portions of the improvements may be used without others.

Having thus described my invention, I claim:

1. A device of the class described having the combination with a suspension rope, of a pulley to receive a portion of the rope, a spring adapted to rotate said pulley to draw the rope, means to stop the rotation of said pulley, and a free loop of variable extent being formed of the rope by the rotation of the pulley.

2. A device of the class described having the combination with a suspension rope, of a pulley to receive a portion of the rope, a spring adapted to rotate said pulley to draw the rope, means to stop the rotation of said pulley, a free loop of variable extent being formed of the rope by the rotation of the pulley, and means to press the rope against said pulley.

3. A device of the class described having the combination with a suspension rope, of a pulley to receive a portion of the rope, a spring adapted to rotate said pulley to draw the rope, means to stop the rotation of said pulley, a free loop of variable extent being formed of the rope by the rotation of the pulley, and resilient means to press the rope against the pulley.

4. A device of the class described having the combination with a suspension rope, of a pulley to receive a portion of the rope, a spring adapted to rotate said pulley to draw the rope, means to stop the rotation of said pulley, a free loop of variable extent being formed of the rope by the rotation of the pulley, and spring pressed means to apply pressure of the rope against the pulley.

5. A device of the class described having the combination with a suspension rope, of a pulley to receive a portion of the rope, a spring adapted to rotate said pulley to draw the rope, means to stop the rotation of said pulley, a free loop of variable extent being formed of the rope by the rotation of the pulley, a roller, a pivoted arm carrying said roller, and a spring actuating said arm to apply pressure of said roller upon said rope and against said pulley.

6. A device of the class described having the combination with a suspension rope, of a casing for the device, means to secure the rope to the casing, a rotatable pulley, a portion

of the rope being passed around the pulley, means to position a portion of the rope in said casing whereby the axis of said pulley is disposed in alignment with the vertical portion of the suspension rope, a spring adapted to rotate said pulley to draw the rope, means to stop the rotation of said pulley, and a free loop being formed of the rope between said securing means and the pulley.

7. A device of the class described having the combination with a suspension rope, of a casing for the device, means to secure the rope to the casing, a rotatable pulley, a portion of the rope being passed around the pulley, means to position a portion of the rope in said casing whereby the axis of said pulley is disposed in alignment with the vertical portion of the suspension rope, a spring adapted to rotate said pulley to draw the rope, means to stop the rotation of said pulley, a free loop being formed of the rope between said securing means and the pulley, and spring pressed means to apply pressure of the rope against the pulley.

8. A device of the class described having the combination with a suspension rope, of a casing for the device, means to secure the rope to the casing, a rotatable pulley, a portion of the rope being passed around the pulley, means to position a portion of the rope in said casing whereby the axis of said pulley is disposed in alignment with the vertical portion of the suspension rope, a spring adapted to rotate said pulley to draw the rope, means to stop the rotation of said pulley, a free loop being formed of the rope between said securing means and the pulley, a roller, a pivoted arm carrying said roller, and a spring actuating said arm to apply pressure of said roller upon said rope and against said pulley.

9. A suspension device for an electric lamp cord having the combination of a casing adapted to be secured to any point of the cord, a rotatable pulley, a portion of the cord being passed around the pulley, means to position a portion of the cord in said casing whereby the axis of said pulley is disposed in alignment with the vertical portion of the electric cord, a spring adapted to rotate said pulley to draw the cord, means to stop the rotation of said pulley, a free loop being formed of the cord between said securing means and the pulley, and spring pressed means to apply pressure of the cord against the pulley.

10. A suspension device for an electric lamp cord having the combination of a casing adapted to be secured to any point of the cord, a rotatable pulley, a portion of the cord being passed around the pulley, means to position a portion of the cord in said casing whereby the axis of said pulley is disposed in alignment with the vertical portion

of the electric cord, a spring adapted to rotate said pulley to draw the cord, means to stop the rotation of said pulley, a free loop being formed of the cord between said securing means and the pulley, a roller, a pivoted arm carrying said roller, and a spring actuating said arm to apply pressure of said

roller upon said rope and against said pulley.

In testimony whereof, I have signed my ¹⁰ name to this specification this 20th day of April, 1926.

BENJAMIN DOWICK.
